(57) **CLAIM**

The ornamental design for an artificial implant, as shown and described.

DESCRIPTION

FIG. 1 is a perspective view of an artificial implant showing our new design;

FIG. 2 is another perspective view thereof;

FIG. 3 is another perspective view thereof;

FIG. 4 is another perspective view thereof;

FIG. 5 is another perspective view thereof;

FIG. 6 is another perspective view thereof;

FIG. 7 is another perspective view thereof;

FIG. 8 is another perspective view thereof;

FIG. 9 is a front view thereof;

FIG. 10 is a rear view thereof;

FIG. 11 is a left side view thereof;

FIG. 12 is a right side view thereof;

FIG. 13 is a top view thereof;

FIG. 14 is a bottom view thereof;

FIG. 15 is a cross-sectional view taken along line 15-15 in FIG. 9;

FIG. 16 is a cross-sectional view taken along line 16-16 in FIG. 9;

FIG. 17 is a cross-sectional view taken along line 17-17 in FIG. 13; and,

FIG. 18 is a cross-sectional view taken along line 18-18 in FIG. 13.

The dashed broken lines illustrating portions of the artificial implant that form no part of the claimed design. The dot-dash broken lines define the bounds of the claimed design and form no part thereof.

1 Claim, 14 Drawing Sheets
